CONCRETE FLOOR CONSTRUCTION

Ralph L. Dickey and Henry M. Beatty, Shaker Heights, Ohio, assignors to The Kelley Island Lime and Transport Company, Cleveland, Ohio, a corporation of Ohio

Application May 30, 1944, Serial No. 538,048

3 Claims. (Cl. 72—70)

1

This invention relates to a floor construction for buildings and aims to provide a novel form of re-enforced concrete floor having a reticulated or expanded metal structure embodied therein and which can be constructed more economically than concrete floors produced by the use of conventional solid or imperforate metal pans or forms.

As is understood by those skilled in the building industry, metal pans of a solid or imperforate sheet metal construction are frequently used in constructing concrete floors. These pans are supported in adjacent or continuous relation to each other by suitable shoring or wooden frame so as to provide a form or mold and then pouring concrete over or into such form or mold. After the concrete has become sufficiently set and hardened the shoring is removed and the pans are detached from the concrete floor structure for further use in constructing other floors. The rental for such pans and the labor in removing the same from the floor slab amounts to a considerable item of expense.

The present invention eliminates the need for the above-mentioned rental and removal of the pans and, as another of its objects, provides an improved floor construction embodying a reticulated or expanded metal structure which initially forms a mold for the concrete and becomes permanently united with the slab by being partially embedded therein.

Another object of this invention is to provide a novel floor construction of this kind, in which the reticulated metal members provided for this purpose are of a shape to define alternate voids and concrete-receiving channels.

A further object of this invention is to provide a novel floor structure of the character mentioned, in which a sheet material extending substantially co-extensive with the reticulated metal structure forms a concrete-retaining medium.

Still another object of the invention is to provide a novel floor construction of this character, having sound-absorbing and heat-insulating means embodied therein or applied thereto.

The present invention also provides a pan or form of novel construction which can be used to advantage in the building of concrete floors.

Other objects and advantages of the invention will be apparent from the following description when taken in conjunction with the accompanying sheet of drawings in which—

Fig. 1 is a partial plan view showing reticulated metal members supported so as to constitute a form and which form is ready to receive the concrete;

Fig. 2 is a partial transverse sectional view taken on line 2—2 of Fig. 1;

Fig. 3 is a partial transverse sectional view on a larger scale and showing the floor after the con-

2

crete has been poured and the shoring removed; Fig. 4 is a similar partial transverse sectional view showing a modified form of our floor construction having an acoustical facing or ceiling on the under-side thereof;

Fig. 5 is a partial transverse sectional view similar to Fig. 4 but showing still another form of our floor construction; and

Fig. 6 is a detail sectional view taken on line 6—6 of Fig. 4 and showing a fastening member employed in connection with the acoustical facing or ceiling.

Proceeding with a more detailed description of the invention and referring particularly to the construction illustrated in Figs. 1 to 3 inclusive, we show a floor 10 comprising a concrete slab 11 and a reticulated metal structure or re-enforcing 12 which initially constitutes a mold or form for the concrete and becomes permanently united with the concrete slab at or adjacent the under-side thereof. As will be presently explained in greater detail, the general shape of the form or mold provided by the metal structure 12 is such that the underside of the floor 10 has integral depending ribs or beams 13 thereon with voids 14 between such ribs.

The metal structure 12 comprises a plurality of elongated channel-shaped reticulated members or pans 15 disposed in adjacent or contiguous relation with their channel recesses forming or defining the voids 14. The members 15 are supported on suitable shoring or wooden framing 16 so as to extend in substantially parallel relation to each other with their laterally extending flanges 17 in abutting or overlapping relation. The members 15 have upright longitudinal side walls 18 which form the sides of the voids 14 while the flat tops or webs 19 form arches which span the voids. The side walls or vertical flanges 18 of the adjacent members or pans cooperate with the lateral flanges 17 to define concrete-receiving channels 20 for forming the ribs or beams 13 on the underside of the floor 10.

The channel-shaped members or pans 15, as here shown, each have two of the parallel voids 14 therein which are separated by a longitudinally extending depending flat-sided rib or flange 21 of substantially the same depth as the longitudinal outer side walls 18. The lower edges of the ribs 21 engage the shoring 16 so that these ribs form an intermediate supporting means for the flat tops 19. The ribs 21 can be formed as doubled or folded portions of the members 15 or, if desired, they can be obtained by constructing and arranging these members so that side walls 18 of adjacent members are in face-to-face relation.

The channel-shaped members 15 are of a reticulated construction, as indicated above; and can be made from expanded or perforated sheet

metal. When these members are made of expanded sheet metal it is desirable that they be re-enforced such as by steel wires or rods 22 located on one or both surfaces of the material and extending in a direction transversely of the voids 14. The wires 22 extend as continuous strands across the lateral flanges 17 and the upright outer side walls 18 and also extend across the tops or arches 19 with depending doubled portions 22a of such strands contained in the longitudinal ribs 21. The wires 22 are attached to the reticulated metal at spaced points therealong as by welding or other suitable attaching means. The transversely extending re-enforcing wires 22 extend in parallel relation to each other and are spaced at suitable distances longitudinally of the channel-shaped members 15.

As shown in the drawing the channel-shaped members 15 preferably also include a concrete-retaining medium in the form of paper or other suitable sheet material 23 extending over the underside of such members. The sheet material 23 follows the shape or contour of the voids 14 as shown in Fig. 2 and can be attached to the underside of the reticulated metal by suitable connecting means such as strips 24 of asphalt applied thereto and which serves as an adhesive. When the depending longitudinal rib 21 is formed by doubling the reticulated metal upon itself, as above mentioned, the sheet material 23 preferably extends around the outside of such rib as shown in Fig. 2.

In using the members 15 in constructing a floor or the like, these members are placed in adjacent or contiguous relation to each other on the shoring or wooden frame 16 so that they define a form or mold onto which the concrete can be poured for forming the slab 11. In Figs. 1 and 2 we show a plurality of the members 15 arranged in such contiguous relation with their voids 14 extending parallel to each other and with the paired side walls 18 defining the concrete-receiving channels 20. The members 15 are preferably attached to the shoring 16, as by means of nails or other suitable connecting members 26 extending therethrough, so as to hold the members against shifting on the shoring. When the members 15 have been thus arranged and secured on the shoring 16 they form a structure which is capable of supporting the weight of workmen who find it necessary to walk on such members in connection with the construction work or in connection with the placing of rods, conduits and other members which are to be embodied in the floor structure.

When the members 15 have been placed and secured in the desired relation, as just explained above, the concrete is poured or otherwise distributed over the structure so as to fill the channels 20 and extend over the arch portions 19 to a desired depth for forming the concrete slab 11. The concrete which fills the channels 20 forms the correspondingly-shaped ribs or beams 13 on the underside of the floor structure. When the concrete is poured or distributed over the members 15 a small amount of the concrete passes through the openings of the metal structure 12 but is prevented from dropping entirely through the structure by the retaining medium 23. The portion of the concrete which passes through the metal structure and is indicated at 27, is retained by the medium 23 so that when the concrete becomes set and hardened the metal structure comprising the channel-shaped members 15 will be permanently united with the slab 11 and will lie

5 at or adjacent the lower side thereof. The structure 12 will thus be embedded, or partially embedded, in the concrete and will constitute a metal re-enforcing means therein.

After the lapse of a suitable period of time for the concrete to become sufficiently hardened, the shoring 16 is removed and the projecting ends of the nails or fastening members 26 can be clipped off. The paper or other sheet material constituting the concrete-retaining medium 23 is preferably left on the underside of the slab although, if desired, this medium could be stripped from the floor structure.

It will be understood, of course, that the above described channel-shaped members 15 can be of any desired size or shape depending upon various factors or requirements in the handling or fabricating of these members and upon various factors or requirements of the concrete slab of which they are subsequently to become a part.

20 In Fig. 4 of the drawings, we have shown a floor 30 of a construction similar to that above described but in which a facing or ceiling 31 has been applied to the underside thereof. The ceiling 31 may comprise a generally flat backing structure 32 formed of conventional metal lath and one or more coats of plaster 33, preferably an acoustical plaster, applied to such backing. In obtaining the modified construction illustrated in Fig. 4, the backing material or lath 32 is placed 25 on the shoring 16 before the channel-shaped members 15, which constitute the metal structure 12, are placed thereon. The backing 32 is preferably attached to the metal structure 12 by suitable clips or fasteners 34. The fasteners 34 are applied to the metal lath 32 so that when 30 the channel-shaped members 15 are placed thereon, the arms 35 of such fasteners will extend through the latter and can be bent or clinched, as shown in Fig. 6, for uniting the backing with such channel-shaped members. The backing 32 can also be wired or otherwise connected to the bottoms of the re-enforcing ribs 21. The fasteners 34 preferably also have a prong or tang 36 thereon which can be driven or pressed into the shoring 16 for holding the metal structure 12 and the backing 32 against shifting on such shoring during the building of the floor. The prongs 36 are preferably of a length such 35 that when the plaster 33 has been applied to the backing 32, they will be concealed in the plaster. The prongs 36 are preferably of a length such that when the plaster 33 has been applied to the backing 32, they will be concealed in the plaster.

40 In the modified construction of Fig. 4, as just described, it will be seen that the facing or ceiling 31 extends across the bottoms of the depending ribs 21 and the concrete-receiving channels 20 by spanning the voids 14. The face or ceiling 31 thus provides the underside of the floor with a neat and finished appearance and has heat-insulating and sound-absorbing properties. The 45 acoustical plaster 33 can be any one of various plasters having these characteristics, for example, it can be a plaster having numerous cells or bubbles therein such as the acoustical plaster disclosed in co-pending application Serial No. 439,876, filed April 21, 1942, now abandoned.

50 In Fig. 5 of the drawings we show another form of our floor construction which is substantially identical with that of Fig. 4 except that the backing structure 38 of the facing or ceiling 39 comprises a preformed sheet or slab of fibrous material having sound-absorbing and heat-insulating properties and which also forms a suitable backing for the acoustical plaster 40. The fibrous 55 backing sheet 38 is attached to the metal struc-

ture 12 of the floor slab 11 by the use of suitable fasteners such as the above described clips 35.

From the foregoing description and the accompanying drawing it will now be readily understood that we have provided a novel floor construction comprising a concrete slab and a reticulated metal structure which initially constitutes a form or mold for the concrete but becomes permanently united with the slab at or adjacent the underside thereof. It will also be seen that when it is desired that the floor have sound-absorbing and heat-insulating qualities, these features can be readily obtained by the application of a sound-absorbing and heat-insulating facing or ceiling thereto in the manner explained above. Furthermore, it will now be understood that our invention also provides a form of novel construction which can be used to advantage in the building of concrete floors or the like.

While we have illustrated and described our novel floor construction in more or less detail, it will be understood, of course, that we do not wish to be correspondingly limited in scope, but regard our invention as including all changes and modifications coming within the spirit of the invention and the scope of the appended claims.

Having thus described our invention, we claim:

1. In a floor construction, a structure comprising a plurality of elongated members formed of expanded metal and having transverse web and depending side wall portions defining an upwardly arched cross-sectional shape, said members being disposed in contiguous substantially parallel relation with side wall portions of adjacent members defining concrete-receiving channels therebetween and the side wall portions with the web forming intervening voids, the transverse webs of said members having doubled portions intermediate said depending side wall portions and forming depending longitudinal ribs of a depth substantially equal to the depth of said depending side wall portions, a facing of imperforate sheet material connected to said members and disposed relative thereto so as to lie closely adjacent to but wholly beneath the said members and to substantially follow the cross-sectional shape defined by said web, rib and side wall portions, and a slab of concrete extending over said voids and substantially filling said channels, said members being adapted to be supported so as to initially constitute a mold for said concrete in which said longitudinal ribs support said transverse web portions at an intermediate point thereof and said imperforate sheet material forms a retainer for the concrete and said members being permanently united to the underside of said slab by being partially embedded therein.

2. In a floor construction, a structure comprising a plurality of elongated members formed of expanded metal and having transverse web and depending side wall portions defining an upwardly arched cross-sectional shape, said members being disposed in contiguous substantially parallel relation with side wall portions of adjacent members defining concrete-receiving channels therebetween and the side wall portions with the web forming intervening voids, the transverse webs of said members having doubled portions intermediate said side wall portions and forming depending longitudinal ribs of a depth substantially equal to the depth of said depending side wall portions, reinforcing wires lying on one side of said expanded metal and attached thereto, said

wires being spaced apart longitudinally of said members and extending transversely thereof and following the cross-sectional shape defined by said web, rib and side wall portions, substantially imperforate sheet material connected to said members and disposed relative thereto so as to lie closely adjacent to but wholly beneath the said members and to substantially follow the cross-sectional shape defined by said web, rib and side wall portions, and a slab of concrete extending over said voids and substantially filling said channels, said members being adapted to be supported so as to initially constitute a mold for said concrete in which said longitudinal ribs support said transverse web portions at an intermediate point thereof and said imperforate sheet material forms a retainer for the concrete and said members being permanently united to the underside of said slab by being partially embedded therein.

20 3. A form for use in concrete floor construction comprising an elongated member made of expanded metal and having transverse web and depending side wall portions defining an upwardly arched channel-shaped cross section, the transverse web of said member having doubled portions intermediate said depending side wall portions and forming a substantially flat-sided double-thickness depending longitudinal rib lying in a substantially vertical plane of a depth substantially equal to the depth of said side wall portions and adapted to support said transverse web at an intermediate point thereof, a plurality of longitudinally spaced reinforcing wires lying on one side of said expanded metal and attached thereto, said wires extending transversely of said member and following the channel-shaped cross section defined by said web, rib and side wall portions and including depending double-thickness portions extending into said rib, and substantially imperforate sheet material attached to said member and disposed relative thereto so as to lie closely adjacent to but wholly below the expanded metal and following the channel-shaped cross section defined by said web, and side wall portions and including substantially flat sheet portions lying against opposite sides of said rib and a connecting portion for said sheet portions extending around the lower edge of said rib.
